UNITED STATES PATENT OFFICE

FRANK G. LONG, OF ROCKCASTLE, ALABAMA

PIPE CLEANER

Application filed January 7, 1929. Serial No. 330,891.

This invention relates to means for cleaning from the interior of pressure pipe lines such as the pressure lines in mines or city water supply means, the sediment of a semi-solid or viscous-like nature which accumulates thereon from the passage of water therethrough or by rust, for example.

The invention is more particularly concerned with and has for its object the provision of a device of this character constructed to cause removal of such sediment from the pipe interior by the action of the pressure fluid of the pipe line and arranged to be moved through the pipe lines progressively with the cleaning operation by the normal pressure of the pipe line fluid.

The particular form in which the invention is embodied is designed to traverse pressure fluid pipe conduits whether level or inclined, including bends involving slight angularity approximating a maximum of 12 degrees without attention other than the usual operation of the pump maintaining the normal fluid line pressure. Since the invention operates through and by the normal fluid pressure in the pipe line, it is operative regardless of the length of the line, so long as it is not obstructed in movement by bends of blocking angularity.

The construction and operation of the device is predicated upon the increase of the normal line pressure by reduction of the cross sectional area of the pipe line by the cleaning device inserted therein, this device having provision for utilizing and directing the pressure fluid to wash away the sediment accumulated upon the interior of the line in advance of the cleaning device which is also moved bodily along the pipe line by said pressure fluid progressively with the clearing away of accumulated sediment in advance thereof.

The structural provisions fulfilling these objects and embodying the features above described as well as others, are described more fully in the following detailed specification which is to be read in conjunction with the accompanying drawings forming part thereof and in which:

Figure 1 is a fragmentary longitudinal

section of a pressure fluid line with the cleaner of the present invention inserted therein and appearing in elevation.

Figure 2 is a similar view but with the cleaning device shown in longitudinal section with the section taken on line 2-2 of Figure 1.

Figure 3 is a sectional view similar to Figure 2 but with the nozzle end of the cleaning projectile provided with a tubular pipe extension for washing away loose sediment in advance of the cleaning device to expedite its progress along the pipe line.

Figure 4 is a transverse vertical section through the spray nozzle end of the cleaning projectile, taken on line 4-4 of Figure 3.

The cleaning device is of tubular form and shape similar to a projectile. Its main tubular body portion 1 is open at its rear end and of a diameter appreciably less than the internal diameter of the pipe line 2. Adjacent to its forward end, it is provided with an external collar 3 approximating but slightly less than the internal diameter of the pipe line 2, and forwardly of this collar terminates in a conical head 4 having therein a series of staggered spray openings 5 and 6 drilled preferably at angles of approximately 22½° and 45° respectively, to project jets of pressure fluid against the walls of the pipe line in advance of the collar 3. The end of the conical head 4 is cut off or truncated and is internally threaded to receive the threaded end of a flushing tube 7 (Fig. 3) or a closing plug 8 (Figs. 1 and 2) when the nature of the accumulation is hard and may not be flushed through the tube. Matter accumulated upon the interior of the pipe line is indicated at 9.

This cleaning projectile is preferably made of bronze or other acid resisting metal, the flushing tube 7 and plug 8 being preferably of similar material.

The flushing tube 7 is used when the accumulated deposit on the interior of the pipe line is of a soft nature and washes this deposit or a portion thereof ahead of the cleaning projectile, thereby increasing the movement of the projectile through the pipe line and preventing choking of the jet openings by 100

such soft deposit. The flushing tube is instrumental also in reducing the pressure of the fluid against the obstructing deposit in the pipe by providing a pressure reducing 5 outlet for the water additional to the spray opening in the conical head.

When the matter accumulated upon the interior of the pipe line is not so soft and is not easily dislodged and flushed forwardly 10 by the tube, the latter is not used and the bore in the conical end of the cleaning projectile is closed by the plug 8.

In the use of the cleaning projectile, with both plug and flushing tube, the pressure 15 fluid such as water enters the open rear end of the projectile and sprays out through the series of spray openings 5 and 6 loosening the deposit on the pipe walls. The pressure fluid also flows forwardly over the outer walls 20 of the projectile and, because of the enlarged diameter of the collar 3 and the obstruction presented thereby, is directed as a thin annular pressure fluid stream against the inner wall of the pipe line removing and washing forwardly matter not removed therefrom by 25 the spray jets and cooperating directly with the rearmost row of spray jets, which as shown extend at an angle of approximately 22½ degrees to the vertical in effecting removal of the matter encrusting the pipe walls. 30 The pressure fluid is forced forwardly within the projectile, with its pressure only partly relieved by the jet holes 5 and 6 and by the flushing tube 7, when used, the projectile 35 being moved forwardly along the pipe line as the deposit in advance thereof is washed loose and flushed forwardly by the spray and flushing tube.

The projectile is inserted in the pipe line 40 at its intake end, which is uncoupled by the pressure line temporarily for this purpose and then recoupled after insertion. It travels through the pipe line through the normal pressure of the line as rapidly as the obstructing deposit is loosened and flushed ahead. 45 Where the line presents no stopping bends, it will travel to the outlet end of the line of itself, it only being necessary to maintain the usual fluid pressure of the line. Where bends 50 of sufficient angularity are met which will stop the projectile, it is, of course, necessary to disconnect the line at these bends, and pass the projectile around the bend to the adjacent straight-away.

55 The particular form of cleaning projectile described and shown, while representing a preferred and simple embodiment of the invention, is intended as illustrative, only, and not as restrictive. Structural variation is 60 therefore contemplated in consonance with the spirit of the invention and the scope of the appended claims.

What I claim, therefore, and desire to secure by Letters Patent is:

65 1. A pipe cleaning tool of tubular form

and adapted to be propelled through the pipe by the pressure of the fluid in the pipe, said tool being of less external diameter than the interior of the pipe line to be cleaned, said tool comprising a tubular member open at 70 its rear end and spaced at its outer sides from the wall of the pipe line and having a nose at its front end of substantially reduced diameter and conical form having a plurality of series of spray jet bores extending therethrough at different degrees of angularity to the axis of the tool, said bores being arranged in staggered relation. 75

2. A pipe cleaning tool of tubular form 80 and adapted to be propelled through the pipe by the pressure of the fluid in the pipe, said tool being of less external diameter than the interior of the pipe line to be cleaned, said tool comprising a tubular member open at its rear end and spaced at its outer sides from 85 the wall of the pipe line and having a nose at its front end of substantially reduced diameter and conical form having a plurality of series of spray jet bores extending therethrough at different degrees of angularity to 90 the axis of the tool, said bores being arranged in staggered relation, said tubular member at the rear end of its conical nose having an external collar of slightly less diameter than the internal diameter of the pipe line presenting an obstruction to the flow of pressure fluid between the pipe wall and the exterior 95 of the tubular member and providing a thin annular passage directing an annular jet of pressure fluid forwardly at the edge of the 100 interior wall of the pipe line.
